UNITED STATES PATENT OFFICE

108,493

DESIGN FOR A BOTTLE

Joe C. Fuller, Deerfield, Ill., assignor to King-Fuller Co., Chicago, Ill., a corporation of Illinois

Application July 8, 1937, Serial No. 70,298

Term of patent 14 years

To all whom it may concern:

Be it known that I, Joe C. Fuller, a citizen of the United States, residing at Deerfield, Lake County, Illinois, have invented a new, original, and ornamental Design for a Bottle, of which the following is a specification, reference being had to the accompanying drawing forming a part thereof, and in which:

Fig. 1 is a front view of a bottle showing my new design;

Fig. 2 a side view;
Fig. 3 a rear view;
Fig. 4 a top plan view; and
Fig. 5 a section taken substantially on line 5—5 of Fig. 1.

I claim:
The ornamental design for a bottle as shown.

JOE C. FULLER.
